UNITED STATES PATENT OFFICE

2,180,025

HEAT-RESPONSIVE SWITCH

Victor Weber, St. Louis, Mo., assignor to The Emerson Electric Mfg. Co., St. Louis, Mo., a corporation of Missouri

Application June 24, 1936, Serial No. 86,991

3 Claims. (Cl. 200—124)

The present invention relates generally to circuit breakers or automatic switches, and more particularly to a trip-free thermally-responsive circuit breaker for use in heat-cooperative relation with an energy-translating device.

The invention contemplates the provision of a trip-free thermally-responsive circuit breaker of simple construction, which is adapted to be mounted within the shell of a motor, or other energy-translating devices, and includes mechanism releasable to break the switch contacts actuated either from ambient heat generated in the energy-translating device itself, or from heat generated by an excessive current passing through a heater element included as part of the circuit breaker assemblage.

An object of the present invention is to provide a thermally-responsive trip-free circuit breaker.

Another object is to provide a trip-free thermally-responsive circuit breaker which is adapted to function at a predetermined temperature to interrupt an electrical circuit.

Another object is to provide a trip-free circuit breaker adapted to break contact either from an excessive ambient heat, or from an excessive heat generated in a heater element intimately associated with the circuit breaker.

Another object is to provide a trip-free circuit breaker adapted to break contact upon an excessive heat generated by a heater disposed in intimate association with the circuit breaker.

Another object is to provide a circuit breaker automatically operable at a predetermined temperature to break a circuit which includes manually operable trip-free reset means.

Other objects and advantages will appear from the following description, taken in conjunction with the accompanying drawing, in which

Fig. 1 is a plan view of a preferred embodiment of a circuit breaker constructed in the light of the present invention including in the assemblage a heater element.

Fig. 2 is a side elevation thereof showing the elements in contacting or closed relation.

Fig. 3 is a side elevation thereof showing the elements in open relation.

Fig. 4 is a section on the line 4—4 of Fig. 1.

Fig. 5 is a section on the line 5—5 of Fig. 1.

Fig. 6 is a section on the line 6—6 of Fig. 1.

Fig. 7 is a plan view of a portion of a circuit breaker and heater element assemblage, showing a modified relationship therebetween.

Referring more particularly to the drawing by reference numerals, 10 indicates generally a trip-

free thermally-responsive circuit breaker or switch constructed in line with the present invention, that includes a base 11 which is of a non-conducting material. Holes 12 are disposed through the base for the purpose of receiving bolts, or the like, (not shown) to secure the circuit breaker to a support. A flanged support member 13 is mounted on the base 11 by means of rivets 14, or the like, and includes an attaching portion 15, a vertical portion 16, and a horizontally disposed flange 17. The vertical portion 16 terminates at one end in an extension 18 which has an opening 19 therethrough. A cylindrical hub 20 is fixed to the extension 18 by means of peening over, as at 21, one end thereof. On a reduced portion 22 of the hub 20 there is disposed a ratchet wheel 23 having teeth 24. Between the wheel 23 and the reduced portion 22 is a layer of solder 25 which, under normal temperatures, is adapted to fix the wheel 23 relative to the said hub. A spring blade 26 is fixed to the plate 11 by means of a rivet 27, or the like, and is adapted to lie beneath the flange 17 of the support member 13. A switch blade, generally indicated 28, is secured to the underside 29 of the flange 17 by means of a rivet 30, or the like, and includes an attaching portion 31, a right angularly disposed intermediate portion 32, a horizontally disposed portion 33 which is adapted to lie in cooperating relation to the spring blade 26, and a toe portion 34 which is adapted to selectively engage a tooth 24 of the ratchet wheel 23. Both the spring blade 26 and the switch blade 28 are of resilient material which biases them to open position (Fig. 3), and they make current transferring contact at 29 only when so held by the ratchet wheel (Fig. 2). The spring blade 26 may be called a terminal member and the switch blade a contact member for more definite electrical designation. Of course, both blades are contacts.

An operating member, generally indicated 35, has pivotal connection with the flange 17 by means of a toe portion 37 of the member cooperatively engaging a slot 36 in the flange. The member 35 includes an intermediate portion 38, a handle 39, a first heel 40, a guide projection 41 and a second heel 42. The handle 39 is adapted to move substantially vertically in a slot 43 in the flange 17. The guide projection 41 extends through a slot 44 in the base 11 and cooperates with the handle and its associated slot to guide the member 35 in its substantially vertical movement. The switch blade 28 has a slot 44 therethrough which is adapted to encircle the heel 40.

and the projection 41 to allow relatively free movement between the switch blade and the operating member. The spring blade 26 has a short slot 46 in the free end thereof which is adapted 5 to straddle the projection 41.

A heater element, generally indicated 47, is connected to the vertical portion 16 of the support by a rivet 48, or the like, and to a terminal post 50, thereby being in series with the switch 10 and the circuit. The heater element includes a loop 51 which extends into the interior of the cylindrical hub 20 in heat-transferring relation thereto. Of course, this heater element may be omitted, if desired, for a particular use of the 15 circuit breaker. One lead 53 is connected to the terminal 50, and a second lead 54 is connected to the rivet 27, which thereby serves as the other terminal, the said leads being adapted to connect the circuit breaker in the circuit to be protected. 20

In Fig. 7 there is shown a modified arrangement of a circuit breaker constructed in accordance with the present invention and a heater element. In this set-up a heater element generally indicated 60 having loop portion 61 and irregularly shaped portions 62 is connected to terminals 63 and 64, respectively, which are disposed in spaced relation in the insulating base 11. Leads 65 and 66 serve to connect the heater in its energizing circuit. The terminal post 50 coincides with one of the rivets 14, to which the lead 53 is connected. The other elements of the circuit breaker are as above described. It is thus apparent that in this assemblage the switch is in to 30 control one circuit while the heater element is in a different energizing circuit.

The operation of the device

The circuit breaker of the present invention is particularly adapted for mounting within the 40 casing of a motor, although it is obvious that it may be used with other electrical devices and for other electrical purposes. In its use with a motor, the circuit breaker is mounted in close proximity to the field windings so as to receive heat generated therein and radiated therefrom. The circuit breaker is connected in series in the line, or in the starting or running windings of the motor, dependent upon the type employed in 45 an instant installation and the circuit desired protected. When thus connected and in closed position, current passes in lead 54 and successively traverses the spring blade 26, the contact point 29, the switch blade 28, the support 13, the heater coil 47, and out lead 53. Inasmuch as the easiest path is through the support 13, very little current actually passes through the cylindrical hub 20 and the ratchet wheel 23. These latter elements may, of course, be insulated from the support. 50

As has been indicated above, the ratchet wheel 23 is adapted to be held fixed relative to its supporting cylindrical hub 20 under normal temperatures by the solder 25. When so fixed, it 55 serves as a latch for holding the switch blade 28 in the position shown in Fig. 2. The switch blade is brought to this position and into this relation with the ratchet wheel from an open position in Fig. 3 by manually, or otherwise, pressing the handle 39 downwardly, which, in this movement, carries with it the switch blade 28 and the spring blade 26, inasmuch as the heel 42 bears against the toe 34 of the switch blade and the heel 40 against the free end of the spring blade. It will 70 be observed that this association provides a

trip-free mechanism, for the inherent resiliency of the blades, the heel 40, and the slot 46 cooperate to maintain the blades in open relation during this downward movement. It is not until the handle 39 has been released and allowed to move upwardly that the blades contact at 29, as is shown in Fig. 2, the resiliency of the spring blade 26 pushing the freed operating member upwardly. 5

Assuming that the parts are in the operative 10 relation, as shown in Fig. 2, and the switch installed within the casing of a motor, rise in heat within the casing will, at a predetermined temperature, so soften the solder 25 as to allow the ratchet wheel to rotate upon its cylindrical 15 support, thereby releasing the switch blade 28 to permit it, through its inherent resiliency, to move upwardly with a substantial snap-action 20 to assume the position disclosed in Fig. 3. This upward movement is stopped by the connecting 25 portion 38 of the member 35. Simultaneously with the movement upwardly of the switch blade, the spring blade 26 moves from the position shown in Fig. 2 to that shown in Fig. 3, being stopped finally by the heel 40. Thus, the 30 blades are separated and contact is broken in the switch which, of course, results in interrupting the supply of current to the motor, thereby stopping it. Further, the switch is adapted to open in like manner from heat generated by the 35 heater element 47 from an excessive current passing therethrough, as would be the case should the motor become blocked and the back E. M. F. reduced. 40

It is apparent from Fig. 7 that the circuit breaker may be connected in one circuit and the heater element in another. That is, the circuit breaker may be in the main line while the heater element is in the main or starting winding circuit. 45

Thus, a trip-free thermally-responsive circuit breaker has been provided which, when used with a motor, or the like, is adapted to open at a predetermined temperature upon a gradual rise in heat in the motor, or upon sudden rise 50 in heat generated from an abnormal current through the heating element. Of course, it is adapted to function upon a combination of these two factors, there being only the one release temperature at which the solder fuses. Broadly, 55 a trip-free thermally-responsive circuit breaker has been provided which is adapted to function at a predetermined temperature to interrupt a circuit.

All of the advantages sought and enumerated 60 above are incorporated in the circuit breaker of the present invention, as can now be readily appreciated. The above description, and the accompanying drawing, have been given by way of illustration and example and not by way of limitation, the invention being limited only by the following claims. 65

What is claimed is:

1. A circuit breaker comprising a base of non-conductive material, a support mounted on the 70 base, a terminal blade fixed at one end to the base out of engagement with the support, a resilient contact blade fixed at one end to the support and adapted to be moved into contact with said terminal blade, a trip-free operating handle pivotally connected to the support and adapted to move said contact blade, and a ratchet wheel mounted on said support and normally maintained in fixed relation thereto by solder, said ratchet wheel being adapted to be engaged 75

- by said contact blade when said blades are in operative contact, said ratchet wheel being adapted to release said contact blade to permit it to withdraw from the terminal blade at a predetermined temperature.
- 5 2. A circuit breaker comprising a base of non-conductive material, a support, a terminal blade, a contact blade, a solder-fixed ratchet wheel, and a trip-free operating handle, said terminal blade and support being mounted on said base in spaced relation, said contact blade, ratchet wheel, and operating handle being mounted on said support, said contact blade in current-passing disposition of said elements being restrained by
- 10 said ratchet wheel in a position in contact with said terminal blade, said ratchet wheel being adapted to rotate at a predetermined above normal temperature to release the contact blade to permit it to move away from said terminal blade.
- 15 3. A circuit breaker comprising a base, a sup-
- port mounted thereon, a movable terminal member mounted on the base, a movable contact member having a slot therethrough mounted on the support, said members being biased to non-engaging positions, thermally-responsive locking means for holding said members in positions for engaging relation adapted to release the same at a predetermined temperature, and a trip-free operating member for resetting said members to engaging position after a release, said operating member including means adapted to pass through the slot of the contact member to engage the terminal member, and means adapted to engage the contact member after the first means has passed through and cleared the same, whereby the terminal member will be positively maintained out of engagement with the contact member.
